THE NORRIS PETERS CO., WASHINGTON, D. C.

UNITED STATES PATENT OFFICE.

HARRY E. SHARP, OF ROCKVILLE, CONNECTICUT, AND LOUIS KENTANA, OF BROOKLYN, NEW YORK, ASSIGNORS OF ONE-THIRD TO GEORGE ULRICH, OF HARTFORD, CONNECTICUT.

TOOL FOR MOLDING CORNICES.

No. 851,035.

Specification of Letters Patent.

Patented April 23, 1907.

Application filed February 5, 1906. Serial No. 299,535.

To all whom it may concern:

Be it known that we, HARRY E. SHARP and LOUIS KENTANA, citizens of the United States, residing at Rockville, in the county of Tolland and State of Connecticut, and LOUIS KENTANA, residing at Brooklyn, in the county of Kings and State of New York, have jointly invented certain new and useful Improvements in Tools for Molding Cornices, of which the following is a specification.

This invention relates to tools for molding cornices, whereby corners may be turned and the cornice entirely completed with one and the same tool.

In the accompanying drawings, Figures 1 and 2 and 3 are respectively plan and rear side views of a tool constructed in accordance with our invention. Fig. 4 is a section on line 77 of Fig. 2.

Like numerals designate similar parts throughout the several views.

Frequently it is necessary to change the angles of the sides of the tool—in other words, to adjust said sides so that the said tool may be made to accommodate itself to wall-surfaces and moldings of any sort—and to permit this to be accomplished various means may be employed and one of which will now be described.

Referring to Figs. 1 to 4, inclusive, the numeral 12 designates a strip from which rises a plate 13, to the inclined upper edge of which is secured, by screws 14, one of a series of interchangeable die-plates 15, each of which may have an edge design of any required contour to be reproduced on the molding. Pivoted at 16 to the inner end of the strip 12 are two arms 17-18, and to said arms are either respectively secured or formed integral therewith curved plates 19 and 20, the plate 19 having rack-teeth 21 and the plate 20 rack-teeth 22. Mounted for rotary movement in the end of strip 12 is a shaft 23, having a threaded section 23', said shaft being provided with a knurled finger-grasp 24, by which it may be manipulated. Rigid with the shaft 23 is a pinion 25, and said pinion is in mesh with each of the racks 21 22, so that when the shaft 23 is turned the said racks and the arms 17 and 18 may be moved in or out to adjust the arms 17 and 18 in the manner described. A collar 26 is pinned to the shaft 23 just above the pinion 25, and said

collar and a head 27 of the shaft are supported in bearings of the walls of a chamber 28 in the end of the strip 12 and through which the rack ends of the arms 19 and 20 pass.

To lock the parts just described against movement after an adjustment has been made, a knurled and chambered jam-nut 29 is threaded upon the section 23' of shaft 23, as illustrated more particularly in Fig. 4.

To change the angular position of the side bars 17 and 18, the nut 29 is loosened, and the shaft 23 is turned to cause the pinion 25 thereof to engage the rack-teeth on the side bars, and thus to adjust the same, and after the desired adjustment has been made the nut is again tightened to lock said side bars rigidly in position.

Changes may be made in the various details of the invention without departure therefrom.

Having thus described our invention, what we claim is—

1. A cornice-molding tool, comprising a support, side bars pivoted to said support, overlapping arms projecting from said bars and each having a rack; a pinion journaled in the support; and a molding-die projecting from said support.

2. A cornice-molding tool comprising a support; a molding-die projecting from said support; side bars pivoted to the support; racks rigid with the side bars and projecting laterally from said side bars; a pinion engaging said racks; and means for locking said pinion.

3. The combination, with a pair of pivoted side bars, of a support connected to said side bars; a molding-die carried by said support; arms projecting from the outer ends of the side bars and each having a rack; a shaft journaled in the support; a pinion carried by said shaft and in engagement with the racks; means whereby the shaft may be rotated; a collar on the shaft; and a chambered jam-nut threaded upon the shaft adjacent to said collar.

In testimony whereof we affix our signatures in presence of two witnesses.

HARRY E. SHARP.
LOUIS KENTANA.
